UNITED STATES PATENT OFFICE.

CHESTER M. ANGELL, OF CHICAGO, ILLINOIS, ASSIGNOR TO VESTA ACCUMULATOR COMPANY, OF CHICAGO, ILLINOIS, A CORPORATION OF ILLINOIS.

BATTERY-VENT.

1,301,993.

Specification of Letters Patent. Patented Apr. 29, 1919.

Application filed September 6, 1918. Serial No. 252,932.

To all whom it may concern:

Be it known that I, CHESTER M. ANGELL, a citizen of the United States, residing at Chicago, in the county of Cook and State 5 of Illinois, have invented certain new and useful Improvements in Battery-Vents, of which the following is a specification.

The present invention relates to vent mechanism for storage batteries and its general object is to provide a simple means for 10 permitting the escape of gases from the battery and preventing the escape of liquid therefrom.

It is the particular object of this invention 15 to prevent the escape of liquid not only from inverted cells, but also from cells that may be laid upon their side or even tilted at a less angle.

The invention will be more fully described in the annexed specification and more particularly pointed out in the claims.

In the drawings which form a part of the specification,

Figure 1 is a vertical section showing a 25 device embodying the invention in normal operation;

Fig. 2 a vertical section similar to Fig. 1, showing the device in closing position, and

Fig. 3 is a perspective view of a detail.

In the drawings 1 represents a one-piece cover plate of a battery cell. This plate has the usual openings 2 and 2' through which extend the binding posts (not shown) and an opening 3 adapted to receive the vent mechanism forming the subject matter of the present invention. This vent mechanism consists preferably of three parts, namely a 30 plug 4 having a flaring or funnel shaped recess 8, a top plate 10 having a central vent opening 12 and a sealing element 15 preferably of lead, hard rubber or other suitable material and shaped to loosely fit the flaring recess 8.

The plug 4 has a screw-threaded tenon 5 adapted to fit the screw-threaded opening 3 in the cover plate 1 and a circular shoulder 6 to fit tightly against the cover plate. The lower portion of the plug 4 is preferably hollowed out to form a recess 7. At the upper end of the plug 4 is provided a circular seat 9 adapted to receive the top plate 10. Intermediate the flaring recess 8 and the seat 9 is formed a short cylindrical portion

11, the significance of which will be subsequently brought out.

Intermediate the recesses 7 and 8 and interconnecting them is a passage 13 of small diameter to form a vent opening similar to and in alinement with the vent opening 12 in the top plate 10.

The space of the recess 8 is substantially taken up by the sealing element 15 which is approximately a truncated cone. Near the base this cone is provided with a short cylindrical portion 14 of slightly smaller diameter than the cylindrical portion 11. The conical surface of the element 15 is provided on opposite sides with slightly flattened portions 16 to form slight clearances and thereby establish a permanent communication between the passage 13 and the vent opening 12, the conical element 15 being of such height as to leave normally a small space below the top plate 10.

When the cell is in normal upright position as indicated in Fig. 1, the gases pass through the clearance spaces 16 to the space above the element 15 and out through the vent opening 12. When the cell is tilted to such an extent that the liquid could flow 75 through the passage 13, the conical sealing member 15 will slide down the wall of the recess 8 and the cylindrical portion 14 will pass into the cylindrical portion 11 of the recess 8 while the upper surface of the element 15 will close the vent opening 12 in the top plate. Since the recess 8 and the element 15 are conical, the closing action will 80 take place no matter in what direction the cell is tilted.

I prefer to make the cylindrical portion 14 slightly longer than the cylindrical portion 11 so that the upper face of the element 15 will positively close the opening 12 before the element 15 has reached its extreme 85 sliding position along the wall of the recess 8.

If desired a soft rubber washer may be attached to the upper surface of the sealing element or to the lower surface of the plate 10 to make the seal more efficient.

While the vent passages along element 15 are formed by machining, they may be formed in many other ways. In place of straight vent passages spiral or irregular 105 passages may be used.

It is understood that within the scope of the invention many changes may be made in the detail arrangement.

I claim:

5. 1. Vent mechanism comprising a funnel-shaped element, a cover plate therefor having a vent opening and a conical sealing member in the funnel-shaped element adapted to have sliding motion therein, said 10 conical sealing member and funnel-shaped element being constructed to establish a gas passage therebetween.
15. 2. Vent mechanism comprising a funnel-shaped element, a cover plate therefor having a vent opening, a conical sealing member in the funnel-shaped element adapted to have sliding motion therein, and means on the said sealing member to define a gas passage between it and the wall of the funnel-shaped element.
20. 3. Vent mechanism comprising a tubular body defining a substantially conical passage, a cover plate across the flaring mouth of the tubular body having a vent opening,

a conical sealing element substantially filling the conical passage, but having limited sliding motion therein toward and away from the cover plate whereby the said vent opening may be opened and closed, and means on the sealing member to define a gas 30 passage between it and the wall of the conical passage when the vent opening is uncovered.

4. Vent mechanism comprising a tubular body defining a substantially conical passage, a closure across the flaring mouth of the tubular body having a vent opening, a conical sealing element having a flat base and adapted to have limited sliding movement in said conical passage toward and 40 away from the said closure whereby the said vent opening may be opened and closed by the flat base and means for defining a gas passage between the wall of the conical passage and the conical element when the vent 45 opening is uncovered.

In testimony whereof, I affix my signature.
CHESTER M. ANGELL.
